UNITED STATES PATENT OFFICE.

HENRY PEARSON, OF SPRINGFIELD, MASSACHUSETTS, ASSIGNOR TO GEORGE A. DENHAM,
OF BOSTON, MASSACHUSETTS.

COMBINED TRAP-DOOR ABUTMENT AND LOCKING MEMBER.

No. 874,426.

Specification of Letters Patent.

Patented Dec. 24, 1907.

Application filed May 8, 1907. Serial No. 372,531.

To all whom it may concern:

Be it known that I, HENRY PEARSON, a citizen of the United States, residing at Springfield, in the county of Hampden and State of Massachusetts, have invented certain new and useful Improvements in a Combined Trap-Door Abutment and Locking Member, of which the following is a specification, reference being had therein to the accompanying drawing.

My invention relates to a device for use in structures, such as sleeping cars and ships, wherein adjacent trap-doors of adjacent berth-receiving pockets are raised from horizontal to vertical position and then arrested and locked in that position.

The objects of my invention are to prevent a trap-door from being carried past its proper upright position and so straining it on or from the hinges which connect it with the floor portion of the structure; to make the abutment serve as one member of a lock whereby the trap-door is locked in vertical position; to make one abutment serve for arresting the upward movement of two adjacent trap-doors so that the latter, when in vertical position, shall have a partition-receiving space between them; and to provide the abutment with a garment-hook or the like, if such is desired.

Referring to the drawings, Figure 1 shows my new device in side elevation; Fig. 2 is a front elevation of the device detached, a part being broken away to show the interior bolt-receiving recess; and Fig. 3 is an under plan view of the device.

In the drawings, A is the base and H an upwardly-extending, integral garment-hook. Base A has the opposite walls 1, 2, which serve as abutments, and a laterally-extend-

ing flange 3 provided with screw-holes, whereby the device may be attached to the side wall of the structure. This flange is towards the rear side of base A, so that the abutment-forming shoulder 2 extends forwardly of the flange when the device is in position of use. Hook H is preferably formed with a lower integral and forwardly-projecting hook 4, the hook H also being on the front side of base A, which is formed with a horizontal wall 5 preferably provided with screw-holes, as shown, for additional attachment of the device to the structure on which it is to be mounted. The underside of base A is cut out to form a bolt-receiving chamber C, as indicated in Figs. 2 and 3. The inner sides 6, 6, of the abutment-forming walls 1, 2, form bearings for bolts of a locking device that is complementary to the device illustrated.

What I claim is:

1. As a new article of manufacture, a combined abutment and locking member comprising a base portion having oppositely-disposed, abutment-forming side walls; and a bolt-receiving chamber or space therein-between.

2. As a new article of manufacture, a combined abutment and locking member comprising a base portion having oppositely-disposed, abutment-forming side walls; and a bolt-receiving chamber or space therein-between; said abutment having an integral garment-support on its front side.

In testimony whereof I have affixed my signature in presence of two witnesses.

HENRY PEARSON.
